JOHN T. JOHNSON, OF WORCESTER, MASSACHUSETTS, ASSIGNOR OF ONE-HALF TO
VERNER G. ANDERSON, OF WORCESTER, MASSACHUSETTS.

PUMP MECHANISM FOR CARPET-SWEEPERS.

1,080,112.

Specification of Letters Patent.

Patented Dec. 2, 1913.

Application filed May 1, 1913. Serial No. 764,818.

To all whom it may concern:

Be it known that I, JOHN T. JOHNSON, a citizen of the United States, residing at the city of Worcester, in the county of Worcester and State of Massachusetts, and whose post-office address is 11 Dover street, in said city, have invented certain new and useful Improvements in Pump Mechanism for Carpet-Sweepers, of which the following is 10 a specification.

My invention relates to improvements in the pump mechanism of a pneumatic dust remover for use on floors and carpets, and has for its object to provide an auxiliary suction 15 chamber having an inlet located beyond the rear or bottom of the dust bag, in order to permit the pneumatics to increase the suction and cause the same to force straight through the full depth of the bag, and there- 20 by to enable the bag to receive the dust collections in an evenly distributed manner toward its bottom part.

A further object in view is to provide an auxiliary chamber in communication with 25 the pneumatics and located close to the highest point of lifting movement of the latter, and means to control the suction from said chamber whereby the upper part of the dust bag is kept fully distended.

30 The invention consists in the details of construction and combination of parts as hereinafter described and claimed, reference being had to the accompanying sheet of drawings, wherein like reference characters 35 indicate like parts.

Figure 1 is a vertical longitudinal section of a vacuum sweeper, taken on line *w*—*w*. of Fig. 2, showing the parts embodying my improvements, and, Fig. 2 is a transverse 40 section of the device, taken on line *x*—*x*. of Fig. 1.

My improvements are essentially designed for application to the form of carpet sweeper having the ordinary construction of casing 45 —*a*— for inclosing the dust bag —*b*—; the removable suction head —*c*—; the pneumatics —*d*— operated by the connections —*e*— through crank shaft —*f*—, and a handle —*g*— for the operator's use in moving 50 the device over the surface to be cleaned. At a point near the back of the casing —*a*— I divide its suction chamber —*a*¹— by a transverse partition —*a*²—, in order to provide an auxiliary suction chamber —*a*³—. 55 The partition —*a*²— has a long opening

—*a*⁴— which extends near to the sides of the casing, to receive the suction from the dust bag —*b*—. The longitudinal center of the opening —*a*⁴— is in alinement to the centers of the mouth —*b*¹— of the dust bag and 60 elongated slot —*c*¹— of the suction head —*c*—. Each pneumatic —*d*— has an upper movable leaf —*d*¹— and a lower leaf —*d*²—, which is secured to the top of the casing and provided with a large oblong opening 65 extending longitudinally of each pneumatic and from near the working end thereof, as at —*h*—, to surround a flap valve —*i*—. The valve —*i*— controls ports —*j*, —*j*— formed through the top of the casing —*a*— 70 and communicating with the auxiliary chamber —*a*⁴—, and said valve has one end secured on said casing and its free end movable on screws which form stops, as —*k*—, to limit the upward movement of said valve 75 above its said ports —*j*—. Having the controlling valve —*i*— arranged to have a free portion lift at a point close to the large end of the pneumatic, permits of greater suction around this portion of said valve after 80 being brought to an opened position against the stops —*k*—.

As the sweeper moves along the surface of the floor or carpet a continuous and partial vacuum is created in the chambers —*a*¹— 85 and —*a*³— which draws the air and dust through the inlet —*c*¹— of the nozzle and into the bag —*b*—, and from the latter the suction takes the air through the inlet —*a*⁴— of the auxiliary chamber —*a*³—, 90 through the valve-controlled-ports —*j*—. The air is forced by the bellows or pneumatics through valve-controlled-outlets —*o*—, formed in the upper leaf of each pneumatic, from whence the air passes from beneath a cover —*p*— of the device and from the rear of the same. The relative increase of length of the pneumatics, afforded by the extra chamber —*a*³—, permits of a corresponding increase of space for their movable leaves to travel, and results in greater power to be had by the pneumatics without enlarging the normal distance between the surface —*s*— and highest point —*t*— of the sweeper. Having the inlet —*a*⁴— located at the rear of the dust bag, as shown, 100 permits the air draft to pass in a straight direction through said bag to this point of location of said inlet, thus maintaining the bag in an inflated condition to receive its 105 110

dust collections, and thereby avoiding the use of a screen within the chamber —*a*— to prevent the bag closing against ports in said chamber as in the ordinary construction.

To form a minimum distance height of the device, between the surface —*s*— and extreme upper part of its cover, as at —*t*—, I provide a flat metallic member —*v*— which is bent a quarter turn at its center part, in order to have one portion secured flat upon the upper movable leaf —*d*— of each pneumatic and the other portion projecting horizontally and pivotally connected to the crank-rod —*e*—, thereby reducing the space between said leaf and the cover —*p*—, when each pneumatic is distended.

Having described my improvements, what I claim and desire to secure by Letters Patent, is:—

In combination with the crank-shaft and rod connection therefrom, a casing, an auxiliary chamber extending transversely of the

latter and near to the shaft, and said chamber having a longitudinally-arranged air inlet, a horizontal bellows having its larger working end above and projecting rearwardly of the said chamber, ports formed in the top of the casing and leading from the said chamber, a flat pneumatic valve to control the suction from the ports to the bellows, said valve having one end secured to the casing and its unattached end provided with a perforation, a screw member loosely passing through the latter and secured to the casing, and said member to form a stop to limit the opening movement of said valve, and the member —*v*— for attaching to the rod connection, substantially as set forth.

In testimony whereof I affix my signature in presence of two witnesses.

JOHN T. JOHNSON.
